CLAIM

The ornamental design for an armchair, as shown and described.

DESCRIPTION

FIG. 1 is a front elevational view of the armchair showing our new design;

FIG. 2 is a left side elevational view, the right side elevational view being a mirror image thereof;

FIG. 3 is a rear elevational view;

FIG. 4 is a top plan view;

FIG. 5 is a bottom plan view; and

FIG. 6 is a perspective view thereof.
